GEOCHEMICAL METHOD

Dirk Richard Clews, Downsview, Ontario, Canada, assignor to Barringer Research Limited, Rexdale, Ontario, Canada
No Drawing. Filed Apr. 26, 1962, Ser. No. 191,682
8 Claims. (Cl. 23—230)

The invention relates to a geochemical method of prospecting for oils, gases and bituminous deposits.

Geochemical prospecting methods of various types are known in which attempts are made to detect the presence of underlying deposits of oil and the like by means of soil sampling. Some such methods are intended to locate the presence of gaseous, liquid or solid hydrocarbon. Other such methods have been designed to locate the presence of trace elements originating from such oil deposits, and attempts have been made to detect the presence of micro-organisms feeding on hydrocarbons escaping from such deposits. However, the majority of such methods have been disadvantageous for various reasons. Thus, in many cases, they have proved to be both slow and expensive in operation rendering extended surveys uneconomical. In addition, the majority of such methods have been subject to considerable difficulties in interpretation and, in some cases, have produced results which have been both erroneous and misleading. One of the more significant problems has been in connection with the so-called "annular anomaly" which has been noted on many occasions and is fully discussed in various textbooks (see for example Geochemical Methods of Prospecting and Exploration for Petroleum and Natural Gas, Kartsev et al., University of California Press, 1959). In this case, a sporadic anomaly is located around the periphery of an oil deposit, but the centre of the oil deposit is generally characterized by an absence of such anomaly. Results of this type, therefore, give only a problematical indication of the presence of a subsurface oil deposit in the absence of other information. In fact, this result is contrary to what would have been predicted since the strongest anomaly would be expected over the centre of the oil deposit where the escape of gases and liquids therefrom would normally be the strongest. Obviously, it would be desirable to provide a geochemical prospecting method capable of achieving continuous detection of the subsurface oil deposit in order that its full extent can be plotted.

It is now suggested that the reason for the so-called "annular anomaly" is in fact that micro-organisms present in the earth's surface over the oil deposit tend to gather over the centre of the deposit, where the escape of gases and liquids is strongest. In addition, it is noted that the zone of oxidizing conditions in the earth's surface will also tend to deepen over the centre of an oil deposit possibly due to such micro-organism concentration. Since the micro-organisms live on and destroy or alter the hydrocarbon constituents, and since the stronger oxidizing conditions will tend to oxidize or alter the hydrocarbon constituents, the methods utilizing the detection of hydrocarbon constituents, and the methods utilizing the detection of trace element reduction due to the escape of reducing hydrocarbon gases will detect anomalies only around the fringes of the oil deposit while detecting little or no anomaly towards the centre unless the sampling zone is extended downwardly beneath the zone of oxidization. However, other constituents such as organo trace constituents will not be so affected and, according to one embodiment of this invention, may be detected continuously across the entire extent of the oil deposit. While not all trace constituents present in the oil deposit will reach the surface in a detectable form, it has now been found according to this inven-

2

tion, that certain of such trace constituents do in fact reach the surface in a readily detectable form and permit an accurate and economical method of plotting the entire extent of the oil field without the "annular anomaly" which resulted from many prior prospecting methods. Amongst such detectable trace constituents are organo-metallic compounds including for example the volatile metallic porphyrins which are carried upwardly with the liquid and gaseous oil escaping from the oil deposit, and, on reaching oxidation zone at the surface, or near surface, become oxidized and can be detected as organo-metallic compounds present in the soil. Such organo-metallic compounds and their derivatives and oxidation products can also be detected in other media, such as, stream, lake or marine sediments, surface and ground water, and in rock formations both on the surface and in subsurface areas.

In addition to the foregoing, the invention also comprehends the isolation and analysis of oxidation and alteration products of the hydrocarbons themselves caused by the action of the micro-organisms and the oxidation conditions thereon, since this also will afford a method of procuring a continuous anomaly rather than a fringe anomaly at or near the surface.

It is therefore a principal objective of the invention to provide a geochemical method for detecting the presence of oil, gas and bituminous deposits by sampling techniques which is both simple and economical to operate and which is efficient and reliable in use.

More particularly, it is an objective of the invention to provide a geochemical method having the foregoing advantages which is sensitive over substantially all areas of the oil deposit and in areas remote from the deposit.

More particularly, it is an object of this invention to provide a geochemical method having the foregoing advantages which is adaptable to operation on a wide variety of surface materials including soil, water, rock and stream, lake and marine sediment.

More particularly, it is an object of the invention to provide a method having the foregoing advantages which is capable of indicating the class of oil deposit present.

The invention seeks to achieve the foregoing and other advantages which will become apparent from the following description of a preferred embodiment by the provision of the method of detecting the presence of oil, gas and bituminous deposits by sampling from the surface of the earth and comprising: obtaining at least one earth surface sample; treating said sample to separate therefrom any oxidation and alteration products and trace elements of said deposits; and determining the proportions of said products and elements present in said sample.

A preferred embodiment of the invention will now be described by way of example only in order to illustrate the invention.

According to this preferred form of the invention, samples are taken manually or mechanically at equally spaced intervals along a predetermined traverse line and are isolated from one another and marked according to their location. Such samples are preferably taken from the A or B lithological soil horizons wherein oxidizing conditions are present. The samples are then air dried in the laboratory and are preconcentrated by sieving in a mesh of approximately 200 B.S.F. or less sufficient to pass clays, silts and very fine sands and to discard the residue.

An accurately measured portion of each sample is then treated with an organic solvent such as benzene, petroleum ether, carbon tetrachloride, carbon disulphide, or any other organic solvent adapted to dissolve petroleum and its derivatives. The mixture is then treated with an

acid, for example, sulphuric acid, hydrochloric acid, or the like, in order to separate the oxidation and alteration products and trace elements of the oil deposit from the remainder of the sample, and to cause the organic constituents thereof to enter into solution in the organic solvents. The mixture is then emulsified by agitation or ultrasonic means. The mixture is then separated into three phases, solid, acid and organic solvent phase, by centrifuging. The two phases are then separately analyzed and the results are plotted in the sequence of sampling along the traverse line. It will be understood that the analysis in each case is directed to the quantitative determination of the organic and alteration products and trace elements of the oil deposit. Thus, in the case of the organic phase, the analysis is directed towards the metals originating in the organo-metallic compounds and towards the other diagnostic oxidation products of hydrocarbons, and in the case of the acid phase is directed towards so-called leachable metals or more loosely chemically bonded metals present in the earth's surface in the zone of reduc-

5 with 5 ml. of benzene analog grade and mixed thoroughly. The sample and organic solvent was then treated with 10 ml. of five normal hydrochloric acid and mixed thoroughly. The mixture was then emulsified by ultrasonic

5 treatment and subsequently centrifuged at 3000 r.p.m. to separate out the solid, acid, and organic phases respectively. The three phases were then placed in separate containers.

10 The organic phase was then analyzed quantitatively by standard geochemical techniques to determine the quantities of copper, iron, nickel and vanadium.

The acid phase was then analyzed quantitatively by standard geochemical techniques to determine the quantities of copper, iron, nickel and vanadium.

15 Simultaneously a control analysis was run on a similar series of samples taken from portions A to O but without the steps of treating them with organic solvent and acid.

The samples of the control analysis were also subjected to quantitative analysis in respect of the same metals. 20 The following results were obtained:

Results

[Figures are for parts per billion of nickel in sample;
120 is background]

	A	B	C	D	E	F	G	H	I	J	K	L	M	N	O
Benzene Soluble Nickel	120	120	120	1,200	6,000	3,600	3,600	3,600	120	120	120	120	120	120	120
Acid Soluble Nickel	1,000	1,000	5,000	5,000	3,000	2,000	1,000	7,000	10,000	1,000	1,000	1,000	1,000	1,000	1,000
Total Nickel in Untreated Sample	15,000	15,000	15,000	15,000	15,000	15,000	15,000	15,000	15,000	15,000	15,000	15,000	15,000	15,000	15,000

ing hydrocarbon gases escaping around the fringe of the deposit. The latter acid phase analysis will of course result only in an annular anomaly of the type already observed, while the organo phase analysis will result in a continuous anomaly co-extensive with the limits of the annular anomaly. It will be apparent that the above steps constitute a relatively simple and economical method of analysis which may advantageously be carried on, for example, by one man at the rate of approximately a hundred samples or more per day, as compared with prior geochemical methods in which four to ten samples a day was about the maximum that could be achieved, and which used complicated and expensive equipment.

It will also be noted that the above method is readily adaptable to the detection of oxidation and alteration products and trace elements of oil deposits carried in sediments of streams, lakes and seas and in surface and ground water and also in rock formations.

By way of illustration, a description will now be given of a specific test conducted over a known oil deposit.

EXAMPLE 1

A traverse line was established across the oil deposit and extending beyond both peripheries thereof. Portions of soil were then removed along the traverse line at intervals of seventeen hundred feet from the A 1 lithological soil horizon, in that locality, being situate in about the top six inches of the earth's surface. Each portion was placed in a separate container and successively marked A, B, C, D, E, F, G, H, I, J, K, L, M, N, O, respectively.

Portions A, B and C were known to be outside the limits of the oil deposit.

Portions D, E, F, G and H were known to be taken within the limits of the oil deposit and substantially vertically above it.

Portions I, J, K, L, M, N and O were taken beyond the further limits of the oil deposit, all of these portions being, as stated, on a straight traverse line.

In the laboratory each portion was air dried and sieved to separate material below 200 mesh, the remaining material being discarded. From each portion a sample of five grams of sieved material was removed and was treated

35 5 Other metals showed a similar dispersion pattern. The method also applies to other oxidation products of petroleum and also to alteration products thereof.

40 While there has been described what is at present considered a preferred embodiment of the present invention, it will be appreciated by those skilled in the art that various changes and modifications can be made therein without departing from the essence of the invention and it is intended to cover herein all such changes and modifications as come within the true spirit and scope of the appended claims.

45 What I claim is:

1. The method of detecting the presence of oil, gas and bituminous deposits by sampling from the surface of the earth and comprising:

(a) obtaining a series of earth surface samples from spaced locations;
(b) treating said samples to separate therefrom any organo-metallic compounds of said deposits;
(c) determining the proportions of said compounds present in said sample;
(d) and plotting said proportions in relation to said locations.

2. The method of detecting the presence of oil, gas and bituminous deposits by shallow surface soil sampling and comprising:

(a) obtaining a series of soil samples selected from soil lying in the A and B lithological soil horizons at special locations;
(b) treating said samples to separate therefrom any organo-metallic compounds present therein and maintain the same in solution;

(c) testing said solution to determine the quantities of metals therein;
(d) and plotting said proportions in relation to said locations of said samples.

3. The method of detecting the presence of oil, gas and bituminous deposits by shallow surface soil sampling and comprising:

(a) obtaining a series of soil samples selected from soil lying in the A and B lithological soil horizons at special locations;

- (b) treating said samples with an organic solvent to separate therefrom any organo-metallic compounds present therein and obtain solutions thereof in said solvent;
- (c) testing said solution to determine the quantities of metals therein;
- (d) and plotting said quantities in relation to respective locations of said samples.

4. The method of detecting the presence of oil, gas and bituminous deposits by shallow surface soil sampling and comprising:

- (a) obtaining a series of soil samples at spaced locations selected from soil lying in the A and B lithological soil horizons;
- (b) treating said samples with an acid in the presence of an organic solvent to separate therefrom any organo-metallic compounds present therein and obtain solutions of said compounds in said organic solvent;
- (c) testing said solutions to determine the quantities of metals therein;
- (d) and plotting said quantities in relation to the respective locations of said samples.

5. The method of detecting the presence of oil, gas and bituminous deposits by shallow surface soil sampling and comprising:

- (a) establishing a traverse line;
- (b) obtaining a series of earth surface soil samples from locations spaced apart along said traverse line;
- (c) treating said samples to separate therefrom any oxidation and alteration products of trace elements of said deposits;
- (d) determining the proportions of said products present in said samples;
- (e) and plotting said proportions against respective locations on said traverse line to establish a single continuous sequence of samples having higher proportions between sequences of samples having lower proportions.

6. The method of detecting the presence of oil, gas and bituminous deposits by shallow surface soil sampling and comprising:

- (a) establishing a traverse line;
- (b) obtaining a series of earth surface soil samples from locations spaced apart along said traverse line, said samples being selected from soil lying in the A and B lithological soil horizons;
- (c) treating said samples to separate therefrom any oxidation and alteration products of trace elements of said deposits;
- (d) determining the proportions of said products present in said samples;

(e) and, plotting said proportions against respective locations on said traverse line to establish a single continuous sequence of samples having higher proportions between sequences of samples having lower proportions.

7. The method of detecting the presence of oil, gas and bituminous deposits by shallow surface soil sampling and comprising:

- (a) establishing a traverse line;
- (b) obtaining a series of earth surface soil samples from locations spaced apart along said traverse line;
- (c) treating said samples with an acid in the presence of an organic solvent to separate therefrom any organo-metallic compounds present therein and obtain a solution thereof in said solvent;
- (d) determining the proportions of said organo-metallic compounds present in said samples;
- (e) and, plotting said proportions against respective locations on said traverse line to establish a single continuous sequence of samples having higher proportions between sequences of samples having lower proportions.

8. The method of detecting the presence of oil, gas and bituminous deposits by shallow surface soil sampling and comprising:

- (a) establishing a traverse line;
- (b) obtaining a series of earth surface soil samples from locations spaced apart along said traverse line;
- (c) treating said samples with an organic solvent to separate therefrom any organo-metallic compounds present therein;
- (d) treating said samples in said solvent with an acid to obtain a solution of said organo-metallic compounds in said organic solvent;
- (e) determining the proportions of said organo-metallic compounds present in said samples;
- (f) and, plotting said proportions against respective locations on said traverse line to establish a single continuous sequence of samples having higher proportions between sequences of samples having lower proportions.
